(57) CLAIM

The ornamental design for a flip open paint box, as shown and described.

DESCRIPTION

FIG. 1 is a front view of the flip open paint box showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof.

The broken lines in the drawings show portions of the flip open paint box that forms no part of the claimed design.
